(57) **CLAIM**

The ornamental design for a protect sheet of catching surface of baseball glove, as shown and described.

DESCRIPTION

FIG. 1 is a front view thereof;

FIG. 2 is a left side view thereof;

FIG. 3 is a right view thereof;

FIG. 4 is a plan view thereof;

FIG. 5 is a bottom view thereof;

FIG. 6 is a cross sectional view taken along line A—A of FIG. 1;

FIG. 7 is a perspective view of the protecting sheet of FIG. 1 in use with a surface sheet of an outer glove element shown in broken lines and forming no part of the claimed design; and,

FIG. 8 is a perspective view on a reduced scale of the use of the protecting sheet in condition of use with a baseball glove. The broken line showing of a baseball glove is for illustrative purposes only and forms no part of the claimed design.
